[57] **CLAIM**

The ornamental design for a compact toothbrush with interproxbrush and gum stimulator, substantially as shown and described.

DESCRIPTION

FIG. 1 is a front elevational view of a compact toothbrush with interproxbrush and gum stimulator showing my new design;

FIG. 2 is a rear elevational view thereof;

FIG. 3 is a right side elevational view thereof; and the left side view is identical;

FIG. 4 is a top plan view thereof;

FIG. 5 is a bottom plan view thereof;

FIG. 6 is a perspective view thereof;

FIG. 7 is a front elevational view of the compact toothbrush with interproxbrush and gum stimulator with the interproxbrush and gum stimulator portion separated from toothbrush portion;

FIG. 8 is a right side elevational view thereof, and the left side view is identical; and

FIG. 9 is a perspective view thereof.

FIG. 1

FIG. 2

FIG. 3

FIG. 4
